CORSAGE CLIP OR THE LIKE

Joni Lea Lowrie, New York, N. Y.

Application September 27, 1955, Serial No. 38,120

Term of patent 3½ years

(Cl. D17—3)

Fig. 1 is a perspective view of the top, front and right side of a corsage clip or the like, in closed condition, showing my new design.

Fig. 2 is a bottom elevational view thereof.

Fig. 3 is an elevational view of the left side thereof.

Fig. 4 is a rear elevational view thereof.

Fig. 5 is a perspective view thereof in open condition.

I claim:

The ornamental design for a corsage clip or the like, as shown.
